UNITED STATES PATENT OFFICE.

TALBOT C. DEXTER, OF FULTON, ASSIGNOR TO THE DEXTER FOLDER COMPANY, OF NEW YORK, N. Y.

DEVICE FOR CONVEYING SHEETS OF PAPER.

SPECIFICATION forming part of Letters Patent No. 540,240, dated June 4, 1895.

Application filed April 13, 1894. Serial No. 507,359. (No model.)

To all whom it may concern:

Be it known that I, TALBOT C. DEXTER, of Fulton, in the county of Oswego, in the State of New York, have invented new and useful 5 Improvements in Paper-Folding-Machine Attachments to Printing-Presses, of which the following, taken in connection with the accompanying drawings, is a full, clear, and exact description.

10 This invention relates to the class of paper-transferring apparatus which are placed between the delivery end of a printing press and a paper-folding machine and convey the paper by means of traveling endless tapes and are removable from their operative positions to allow them to be used interchangeably with a fly which simply deposits the printed sheets in a pile without folding the sheets.

15 For exemplification of the application of my present invention to the aforesaid paper-transferring apparatus, I have shown it in connection with the two apparatus for which I have obtained Letters Patent of the United 20 States Nos. 505,509 and 506,392. In these as well as in other analogous paper-transferring apparatus placed removably between the printing press and folding machine, the paper-conveying tapes of said apparatus are 25 caused to hang loosely on their carrying-rollers when the apparatus is removed from its operative position, and in this condition the tapes are liable to become tangled, and the operation of replacing the apparatus in its 30 operative position between the printing press and folding-machine is on that account slow and tedious, and in case the tapes have been exposed to a humid atmosphere, it is very difficult to properly adjust to their requisite operative position the brackets which support 35 the tape-carrying rollers, owing to the increased tension of the tapes shortened by the moisture.

The purpose of my present invention is to 40 afford means to allow the aforesaid brackets to be mounted on their supports so as to hold the tapes sufficiently slack to allow them to be examined and adjusted to their respective lineal positions and subsequently adjusted to 45 tighten said tapes; and to that end the in-

vention consists in the combination with a paper-transferring apparatus equipped with paper-conveying tapes, of brackets supporting the tape-carrying rollers mounted on their supports adjustably on lines parallel with the 55 tapes, and levers fulcrumed on said supports and connected to the aforesaid brackets for moving the same to their requisite positions, as hereinafter more fully described and set forth in the claims.

6c In the annexed drawings, Figure 1 is a side elevation of my improvements applied to a paper-folding-machine attachment for which I have obtained Letters Patent No. 506,392, dated October 10, 1893. Fig. 2 is an enlarged 65 side view of the adjustable bracket which carries the upper tape-rollers. Fig. 3 is an enlarged transverse section on line X X in Fig. 1. Fig. 4 is a side view of the attachment of the paper-transferring apparatus to 70 a printing-press shown in my Letters Patent No. 506,392, dated October 10, 1893, embodying my present invention. Fig. 5 is an enlarged side view of the same, and Fig. 6 is a detached plan view of the adjustable support 75 of the roller-supporting bracket.

Similar letters of reference indicate corresponding parts.

Referring to Figs. 1, 2, and 3 of the drawings, —C— represents one of the supporting 80 bars of the paper-transferring apparatus placed removably between the delivery end —B— of the printing machine and receiving end of the folding-machine —A—.

—I— represents one of the brackets which 85 supports the tape-rollers. Said bracket was heretofore mounted adjustably upon a metallic plate which was fastened to the top of the bar and projected over the sides thereof to form longitudinal guides which were 90 embraced by grooved flanges on the sides of the bracket and consequently in attaching and removing the bracket from the bar, it was necessary to slide the bracket the entire length of the plate. A spring depressed pin 95 —b— connected to the bracket engages one of a plurality of sockets —a— in the stationary plate and retains the bracket in its desired position.

One of the objects of my present invention 100

is to facilitate the attachment and detachment of the bracket —I— to and from the bar —C— and for that purpose I mount on said bar a longitudinally adjustable metallic bar —D— locked in its adjusted position by the spring depressed pin —b— connected to said bar and passing through the same and into one of a plurality of sockets formed in the main bar —C— as shown in Fig. 3 of the drawings. The upper end of this supplemental bar is formed with a nose or upward projecting tongue —t— leaving a recess —t'— under it. Upon said supplemental bar is mounted the bracket —I— the upper end of the base of which is formed with a downwardly and rearwardly projecting hook —h— which engages the tongue —t—. Said tongue and hook being very much shorter than the plate and grooved flanges heretofore employed for retaining the bracket on the bar, greatly facilitates the attachment and removal of the bracket when desired.

To sustain the bracket —I— and supplemental bar —D— laterally upon the main bar —C—, I attach to the supplemental bar metal straps —c— which embrace the main bar so as to prevent the supplemental bar from being lifted from the main bar by the strain of the tapes. Said straps extend upward from the supplemental bar and embrace the sides of the bracket. The lower end of the base of the bracket is formed with a rearwardly projecting heel —d— across the top of which bears a pin —e— attached to the two straps —c— at opposite sides of said heel, said pin serving to retain the lower end of the bracket down upon the supplemental bar. The bracket in this case is thus mounted on the primary supporting bar —C— adjustably on a line parallel with the tapes by means of the supplemental bar —D—.

To facilitate the operation of pushing the bracket —I— toward the upper end of the bar —C— so as to tighten the tapes, I pivot to said bar a lever —l— and connect said lever with the supplemental bar —D— by a stiff strap —l'— pivotally connected to said parts. By raising the pin —b— out of the socket —a— and pushing upward the free end of the lever the supplemental bar —D— with the bracket —I— riding thereon is conveniently pushed toward the upper end of the bar —C—, and is subsequently retained in its adjusted position by the pin —b— dropping into one of the sockets —a—.

When my present invention is to be applied to the bracket-support shown in Figs. 4 and 5 of the drawings, I mount the supplemental bar —D— on the horizontal plate —C'— which is supported on the arm —A— suspended from the feed-board of the press

and is provided with the sockets —a— in its top as shown in Fig. 6 of the drawings.

The connection of the supplemental bar —D— to the plate —C'— is substantially like the connection of said bar to the main supporting bar —C— hereinbefore described. The lever —l— in this case is fulcrumed on the plate —C'— and connected to the supplemental bar —D— by the strap —l'— and the adjustment of the supplemental bar with the bracket riding thereon is effected by raising the locking pin —b— and manipulating the lever —l— in the manner hereinbefore described. 75

What I claim as my invention is—

1. In a paper-transferring apparatus placed removably between the delivery end of a printing press and receiving end of a folding-machine, an adjustable tape-roller support 80 consisting of a bar or plate supported in proximity to the aforesaid end of the printing press, a supplemental bar mounted longitudinally adjustable on said bar or plate and provided with a forwardly projecting tongue 85 on its front end, the tape-roller supporting bracket mounted removably on said supplemental bar and provided with a hook engaging the aforesaid tongue, guides sustaining the supplemental bar and bracket laterally upon 90 its aforesaid bar or plate, a lever fulcrumed on the bar or plate, and a stiff strap connecting the lever to the supplemental bar substantially as and for the purpose set forth.

2. In a paper-transferring apparatus 95 equipped with paper-conveying tapes and placed removably between the delivery end of a printing press and paper-folding machine, the combination of the main supporting bar or plate provided with sockets —a—, the supplemental bar —D— mounted movable longitudinally on said supporting bar or plate and provided with the tongue —t— on its front end, the bracket —I— provided with the hook —h— and the heel —d—, the straps 105 —c— attached to the supplemental bar and sustaining the same and bracket laterally upon the main support, the pin —e— bearing on the heel —d— and connected to the straps at opposite sides thereof, the spring-actuated locking pin —b— connected to the supplemental bar, the lever —l— fulcrumed on the main support, and the strap —l'— connecting the lever to the supplemental bar as set forth and shown. 110 115

In testimony whereof I have hereunto signed my name this 2d day of April, 1894.

TALBOT C. DEXTER. [L. S.]
